United States Patent Office

Des. 218,224
Patented Aug. 4, 1970

218,224

PACKAGE OR SIMILAR ARTICLE

Keith Stewart Carmichael, Wilmington, Del., assignor to
E. I. du Pont de Nemours and Company, Wilmington,
Del., a corporation of Delaware

Filed Nov. 12, 1968, Ser. No. 14,377

Term of patent 7 years

Int. Cl. D9—99

U.S. Cl. D9—184

FIG. 1

FIG. 2

FIG. 1 is a perspective view of a package or similar article showing my new design, and

FIG. 2 is an end elevation thereof.

The side and end not shown are identical to that of FIG. 1 while the bottom is plain with the individual cartons visible through the transparent film.

I claim:

The ornamental design for a package or similar article, substantially as shown and described.
